UNITED STATES PATENT OFFICE.

EDWARD R. BULE, OF NEW YORK, N. Y.

COMPOSITION FOR REMOVING CARBONACEOUS DEPOSITS.

1,120,272.

Specification of Letters Patent.

Patented Dec. 8, 1914.

No Drawing.

Application filed July 10, 1914. Serial No. 850,855.

To all whom it may concern:

Be it known that I, EDWARD R. BULE, a citizen of the United States, and a resident of New York, in the county of New York, 5 and State of New York, have invented certain new and useful Improvements in Compositions for Removing Carbonaceous Deposits, of which the following is a full, clear, and exact specification.

This invention relates to a composition capable of dissolving the binding elements of carbon in internal combustion or explosive engines or motors, so that the carbon deposits, incrustation, or scale, may be conveniently and quickly removed from parts not readily accessible.

In the operation of a motor of this kind, imperfect combustion produces a soot which becomes mixed with the lubricating oil 20 forming a carbonaceous or resinous substance which is baked under the action of the intense heat due to the explosions. This carbonaceous and resinous substance becomes very hard and clings tenaciously to 25 the inner surfaces of the cylinder, piston and valves, and soon offers serious resistance to the proper working of the parts.

It is the object of the present invention to produce a composition which will act 30 quickly upon these substances, reducing them to a powdered form in which they may be blown out.

It is also my aim to produce a composition that may be readily applied or injected 35 into the cylinder without necessitating the dismantling of the motor.

The solvents for resinous and carbonaceous substances, which I find to be most efficacious, such as alcohol, ether, acetone 40 and carbon bisulfid, are all very volatile, and experiments have shown that in order to hold them on the hot inner surfaces of a motor long enough to do their work of reducing the deposits above referred to, it is 45 necessary to combine with said solvents some retarding substance. I have discovered that water is the best retarder that can be used because it does not mix with the lubricating oil or affect the lubrication of 50 the cylinder as petrol products are known to do, and for the further reason that it is converted into steam which tends to loosen the carbon deposits from the metal. I have also found that cyanid of potash, in 55 comparatively small proportion to the water,

may also be used in addition to the water and give beneficial results, especially as said cyanid of potash acts as a cleanser as well as a retarder and removes all oxids from the metal surfaces with which the composition 60 comes in contact.

In my experiments I have found that acetone and carbon bisulfid may be used interchangeably in my improved composition, and that the proportions of the several ingredients may be varied somewhat and still give the desired results.

The following formulas may be taken as indicating approximately the limits of variation which may be made in the proportions of the ingredients without departing from my invention or losing the effects of the same:

Alcohol from 23% to 28% or from 2 oz. to 2½ oz. 75

Acetone (or carbon bisulfid) from 5½ to 5% or from ½ oz. to 3½ drms.

Ether from 1½ to 2% or from ½ oz. to 1½ drms.

Cyanid of potash from 20½ to 15% or 80 from 1½ to 1 oz.

Water 50% or 3½ oz.

It will be observed that according to these formulas the proportions of solvents to retarders may vary from 29½% solvents and 85 70½% retarders to 35% solvents and 65% retarders. Any substantial increase in the proportion of retarders above 70½% will interfere with the action of the solvents, and any substantial increase in the proportion 90 of the solvents above 35% will result in the evaporation of said solvents before they have a chance to act sufficiently upon the carbon. Experiment with a greater proportion of solvents than that named resulted in 95 almost instantaneous evaporation of such solvents, leaving a white precipitate on top of the carbon.

The compound converts the carbon deposits into a powder or soot comprised of 100 fine particles, rather than into a scale or solid lumps, and this powder or soot may be readily blown out through the exhaust ports as soon as the engine is started. There is nothing in the compound to corrode the 105 metal surfaces, the effect of the compound being rather to cleanse and polish such metal surfaces by reason of the presence of cyanid of potash. It will also be observed that none 110 of the elements of the compound are capa-

ble of attacking the lubricating oil or interfering with the lubrication of the parts, which is a very important consideration.

The compound may be readily sprayed into the cylinder through one of the valve ports or the port in which the spark plug is fitted, by any suitable injector. I employ the variety of solvents mentioned in order to meet different conditions found to exist 10 in different motors.

Having thus described my invention, what I claim as new and desire to secure by Letters Patent of the United States is:

1. A composition of the character described, consisting of solvents, including alcohol, ether and acetone, and retarders, including a predominating proportion of water, the proportion of the solvents being between about 29 $\frac{3}{4}$ % and about 35% and 15 the proportion of the retarders being between about 65% and about 70 $\frac{1}{4}$ %.
2. A composition of the character de-

scribed, consisting of solvents, including alcohol, ether and acetone, and retarders, including cyanid of potash and water, the proportion of the solvents being between about 29 $\frac{3}{4}$ % and about 35% and the proportion of the retarders being between about 65% and about 70 $\frac{1}{4}$ %.

3. A composition of the character described, consisting of the following ingredients in substantially the proportions given, namely: alcohol from 23% to 28%, ether from 1 $\frac{1}{4}$ % to 2%, acetone from 5 $\frac{1}{2}$ % to 5%, cyanid of potash 20 $\frac{1}{4}$ % to 15%, and 30 water 50%.

In testimony whereof I have signed my name to this specification in the presence of two attesting witnesses.

EDWARD R. BULE.
